UNITED STATES PATENT OFFICE.

ARTHUR H. BARNES, OF MONTGOMERY CITY, MISSOURI.

FILM HOLDER.

Application filed September 21, 1921. Serial No. 502,171.

To all whom it may concern:

Be it known that ARTHUR H. BARNES, a citizen of the United States of America, residing at Montgomery City, in the county of 5 Montgomery and State of Missouri, has invented new and useful Improvements in Film Holders, of which the following is a specification.

The object of the invention is to provide 10 a simple, inexpensive and efficient device for holding and protecting films and more especially kodak films for mailing and other transportation purposes, and in this connection to provide a device which may be used 15 as an advertising medium for the benefit of film developing houses, to be forwarded to amateur photographers as a means of inducing the latter to enclose and forward their films to the house for development, under 20 conditions insuring the safety and preservation of the films; and with this object in view the invention consists in a construction and combination of parts of which a preferred embodiment is shown in the accompanying 25 drawings, wherein;—

Figure 1 is a perspective view of a film holder embodying the invention in condition for transportation by mail or otherwise.

Figure 2 is a view of the holder in the 30 open or spread condition ready for the reception of a film and showing the inner side thereof.

Figure 3 is a similar view showing the outside of the holder.

The holder consists of a blank 10 of flexible material such as paper or its equivalent having an interior cushioned lining 11 of corrugated paper or its equivalent, said blank being provided at one end with a closure or sealing flap 12, adjacent to which upon a suitable blank 13 may appear the name and address of the developer or developing house, and at the other end with a retaining tongue 14, said sealing flap and 45 retaining tongue being gummed as indicated respectively at 12^a and 14^a for the convenience of the party desiring to forward a film for development.

As indicated by the dotted lines at 15 in Figure 2 a film may be placed upon the corrugated or cushioned inner surface of the blank and secured by means of the gummed tongue 14 whereupon the blank may be rolled to the form shown in Figure 1 and sealed by means of the flap 12 for deposit 50 in the mails or for otherwise carrying to the developer or developing house under conditions protecting the film from being light struck and also from accumulation of dust or contact with objects likely to cause the 55 blurring or injury thereof. Obviously the developed prints or pictures or fixed films may be returned to the sender by the same means or through the same agency and therefore under conditions not requiring the 60 folding thereof or such mutilation as would render them unacceptable to the 65 photographer.

Having described the invention, what is 70 claimed as new and useful is:—

A film transporting holder comprising an elongated sheet, a flap applied to one side of the sheet and at the end thereof, said flap having its end edges spaced from the side edges of the sheet, the said flap being provided around its edge beyond the end of the sheet with an adhesive, the said adhesive being upon that side of the flap which is attached to the side surface of the sheet, a tongue applied to the opposite end of the 75 sheet and having a portion projecting beyond the adjacent end of the sheet, an adhesive carried by the side of the tongue which is disposed away from the adjacent side of the sheet, the side edges of the 80 tongue being spaced from the side edges of the sheet, and the median longitudinal dimension of the tongue being aligned with the median longitudinal dimension of the sheet and aligned with the transverse dimension of the flap which is located midway between the ends of the flap.

In testimony whereof he affixes his signature.

ARTHUR H. BARNES.
